UNITED STATES PATENT OFFICE

RAFFAELE BACCELLIERI, OF PHILADELPHIA, AND AUGUSTO DE RENTIIS, OF COLLINGDALE, PENNSYLVANIA, ASSIGNORS TO BACCELLIERI BROS. MFG. COMPANY, OF PHILADELPHIA, PENNSYLVANIA, A PARTNERSHIP COMPOSED OF RAFFAELE BACCELLIERI AND PETER BACCELLIERI

RATCHET MECHANISM

Application filed February 17, 1930. Serial No. 429,091.

This invention relates to a ratchet mechanism and has particular reference to such mechanism for use with fruit presses and the like.

5 The object of the invention is to provide improved ratchet mechanism for heavy duty.

Another object of the invention is to provide a ratchet mechanism which is more easily operated than mechanisms of that type in use 10 at the present day.

Another object of the invention is to provide a heavy duty ratchet mechanism which may have its parts cast requiring practically no finishing of the parts.

15 Still another object of the invention is to provide a ratchet mechanism which may be readily and economically assembled and in which there are few moving parts so that there is little likelihood of the same getting 20 out of order.

According to the invention the ratchet mechanism comprises a suitable standard having an oil groove which receives a ball bearing, a ratchet wheel suitably mounted for 25 rotation on said ball bearing, an operating head and cam actuated means for reciprocating said head for rotating said ratchet wheel.

The drawings illustrate an embodiment of the invention and the views therein are as 30 follows:

Figure 1 is a side elevation of our improved ratchet mechanism,

Figure 2 is a top plan view of the same, showing the operating lever broken away,

35 Figure 3 is a vertical sectional view taken on the line 3—3 of Figure 2,

Figure 4 is a horizontal sectional view taken on the line 4—4 of Figure 1, and

40 Figure 5 is a horizontal section and may be said to be taken, as indicated, by the line 5—5 of Figure 3.

The ratchet mechanism is mounted on a standard 6 which comprises a base 7, an upright inwardly tapering tubular post 8 and a ball bearing housing 9 at the upper end of said post.

The outer wall 11 of said housing, together with the inner annular flange 12, form 45 an annular cup 13 in which the lower race 14

and the balls 16 and upper race 17 of a ball bearing are housed.

Sufficient oil may be kept within this annular cup 13 to properly lubricate the bearing.

5 The outer wall 11 of the housing 9 has a plurality of lugs 18 extending upward therefrom and which said lugs are undercut at 19 for receiving the head of a bolt 21 which secures a locking plate 22 onto said lug and onto the lower annular flange 23 of the ratchet wheel hub 24.

65 The ratchet wheel hub 24, the ratchet wheel 26 and the standard 27 are integrally formed and said standard is provided with an outwardly extending flange 28 which provides a circumferential groove 29 between the same and the upper face of said ratchet wheel.

This ratchet wheel is provided with an inner and outer circle of holes 31 and 32, respectively, some of the walls of which form 70 abutments for engagement by the pawls 33, as later explained.

75 The reciprocating head 34 whose width is almost equal to the diameter of the ratchet wheel 26 has a recess 36 formed midway of its length and along the two sides of this recess are bearing pads 37. The bearing pads 37 fit within the circumferential groove 29 provided by the flange 28 on the standard 27 and provide for the free and easy reciprocation of the head 34 while always retaining the said head in aligned position.

80 The outer ends of the head are provided with upstanding lugs 38 which have oblong holes 39 in the same for receiving the pawls 33, while said lugs terminate inwardly in upstanding wings 41 which, together with wings 42 on pads 43, provide means for retaining the ends of connecting rods 44 which are pivotally held in position by means of the pins 46.

85 The pads 43 are located between the lugs 38 and the bearing pads 37 and these lugs are also provided with oblong holes 47 for receiving the pawls 33 when a greater speed 90 of the ratchet wheel 26 is desired.

95 The connecting rods 44 have their outer ends terminating in bearing rings 48. These bearing rings are adapted to receive eccentrics 49, carried rigidly upon shaft 51 which 100.

said shaft is journaled in bearings 52 on the ends of arms 53 formed integrally with the said standard 6.

5 The arms 53 have an integrally formed brace 55 between the same and beneath the bearings 52 formed thereon.

10 One of the eccentrics 48 has an operating member 54 secured thereto by means of bolts 56 and this member has integral outwardly extending arms 57 terminating in sockets 58 for the reception of a lever or the like for operating said disks.

15 When the operating member 54 is rotated, the eccentrics 49 will be rotated in the bearings 48 and, on account of their eccentric attachment to the shaft 51, will reciprocate the head 34 and when said head is drawn towards the shaft 51 the pawl 33 on the one side of said head will rotate the ratchet wheel 26 and when the connecting arms 44 move the said head away from the shaft 51, the other pawl will also rotate the ratchet wheel in the same direction.

20 It therefore follows that for each complete revolution of the disk 49 the ratchet wheel will receive two operating impulses. The bottoms of the pawls are tapered and operate in precisely the same manner as the pawls shown in the patent of Raffaele Baccellieri, 30 one of the co-inventors herein, No. 1,513,209, granted October 28, 1924.

25 It is obvious that at the initiation of operation, the ratchet wheel 26 may be rotated by hand, that is to say, by grasping the periphery of the wheel and turning it. As the resistance becomes greater, the ratchet mechanism may be availed of by inserting the pawls 33 in the openings of the pads 43 and in engagement with the inner circle of holes 32.

30 31. The reciprocation of the head will rotate the wheel 26 with some rapidity. As the resistance again increases, these pawls 33 may be moved to the openings 39 in the extreme ends of the head 34 to engage the outer circle of holes 32 which provide for greater leverage than operating in conjunction with the inner circle of holes 31.

35 It will also be seen that if the operating member 54 is oscillated back and forth, sub- 50 scribing an arc of 90°, the ratchet wheel will likewise be rotated in the same manner and the double-ended socket operating member will permit of two persons operating the ratchet wheel in the manner last indicated.

55 The ratchet wheel hub has an axial bore 59 threaded so as to receive a screw which is fastened to any suitable compressing device located on the bottom of the same.

60 This screw and compressing member have not been shown as they form no part of this invention, but may be the same as indicated in the patent above mentioned.

65 This ratchet mechanism is intended for heavy service and the parts are made sturdy so as to withstand all strains which may be

produced by two strong men handling the operating member 54.

Of course, the ratchet mechanism illustrated may be modified in various ways without departing from the invention herein set forth and hereafter claimed.

The invention is hereby claimed as follows:

1. Ratchet mechanism comprising a support, a ratchet wheel mounted on said support, means between said support and said ratchet wheel for providing free and easy rotation of the latter, arms extending out from said support and having bearings in the ends thereof, a shaft in said bearings, an operating head, means in part on said shaft 75 for reciprocating said head to rotate said ratchet wheel, and a ratchet connection between the head and wheel.

2. Ratchet mechanism comprising a support, a ratchet wheel mounted on said support, means between said support and said ratchet wheel for providing free and easy rotation of the latter, arms extending out from said support and having bearings in the ends thereof, a shaft in said bearings, an operating head, eccentric means in part on said shaft 80 for reciprocating said head to rotate said ratchet wheel, and a ratchet connection between the head and wheel.

3. Ratchet mechanism comprising a support, a ratchet wheel rotatably mounted on said support, arms extending out from said support and having bearings on the end thereof, a shaft in said bearings, disks eccentrically mounted on said shaft, an operating head, a ratchet connection between the head and wheel, and means connecting said head and said disks whereby said head is reciprocated to actuate said ratchet.

4. Ratchet mechanism comprising a support, a ratchet wheel rotatably mounted on said support, arms extending out from said support and having bearings on the ends thereof, a shaft in said bearings, disks eccentrically mounted on said shaft, an operating head, ratchet connection between said head and said wheel, and rods connecting said head and said disks whereby said head is reciprocated to actuate said ratchet.

5. Ratchet mechanism comprising a support, a ratchet wheel rotatably mounted on said support, arms extending out from said support and having bearings on the ends thereof, a shaft in said bearings, disks eccentrically mounted on said shaft, an operating head, ratchet connection between said head and said wheel and connecting rods embracing said disks and connecting said head and said disks whereby said head is reciprocated to actuate said ratchet.

6. Ratchet mechanism comprising a support, a ratchet wheel rotatably mounted thereon, arms extending out from said support and journaling a shaft, disks eccentrically mounted on said shaft, an operating

- head, ratchet connection between the head and wheel, means connecting said disks and said head to reciprocate said head and thereby actuate said ratchet, and means for rotating said disks. 5
7. Ratchet mechanism comprising a support, a ratchet wheel rotatably mounted on said support, arms integrally formed with said support and journaling a shaft, disks eccentrically mounted on said shaft, an operating head, ratchet connection between the head and wheel and connecting rods each having one end pivotally mounted to said head and the other end embracing said disks 10 whereby upon the turning of said disks the head is reciprocated to actuate the ratchet. 15
8. Ratchet mechanism comprising a support, a ratchet wheel rotatably mounted on said support, said ratchet wheel having holes 20 intermittently spaced in concentric circles around the same, an operating head, pawls carried by said operating head for engaging said holes of either circle electively to rotate said ratchet wheel upon the reciprocation of 25 said head, and eccentric means carried by said support for providing reciprocating motion to said head. 30
9. Ratchet mechanism comprising a support, a ratchet wheel rotatably mounted on said support, said support having integrally formed arms journaling a shaft, disks eccentrically mounted on said shaft, a reciprocable head, ratchet connection between the head and wheel, connecting rods each pivotally mounted at one end to said head and having a bearing on the other end into which one of said disks is fitted, and means for rotating said disks whereby said head is reciprocated. 35
- 40 10. Ratchet mechanism comprising a support, a ratchet wheel rotatably mounted on said support, said ratchet wheel having a standard, an annular flange on said standard forming with said ratchet wheel a circumferential groove, a reciprocating head slidably mounted in said groove, ratchet connection between the head and wheel, eccentric means carried by said support, and means connecting said head and said eccentric means whereby said head is reciprocated upon the turning of said eccentric means. 50
11. Ratchet mechanism comprising a support, a ratchet wheel rotatably mounted on said support, said ratchet wheel having a standard, an annular flange on said standard forming with said ratchet wheel a circumferential groove, a reciprocating head slidably mounted in said groove, ratchet connection between the head and wheel, arms integrally formed with said standard and journaling a shaft, disks eccentrically mounted on said shaft, and means connecting said head and said eccentrically mounted disks whereby upon the turning of said disks the 55 said head is reciprocated. 60
12. Ratchet mechanism comprising a support, a ratchet wheel rotatably mounted on said support, said ratchet wheel having a standard, an annular flange on said standard forming with said ratchet wheel a circumferential groove, a reciprocating head slidably mounted in said groove, ratchet connection between the head and wheel, arms integrally formed with said standard and journaling a shaft, disks eccentrically mounted on said shaft, means connecting said head and said eccentrically mounted disks whereby upon the turning of said disks the said head is reciprocated, and means for rotating said eccentrically mounted disks. 70 75
13. Ratchet mechanism comprising a support, a ratchet wheel mounted on said support and having a circle of holes intermittently spaced, an operating head, pawls carried by said head adapted to engage the holes in said ratchet wheel at diametrically opposite points, eccentric mechanism for reciprocating said head, said eccentric mechanism bearing such ratio that said ratchet wheel is rotated an amount equal to the distance between successive holes upon each 90° rotation of said eccentric mechanism. 80 85
14. A ratchet mechanism comprising a support, a wheel journaled upon the support and provided with concentrically arranged abutments, a head extending diametrically of the wheel, means to reciprocate the wheel laterally relative to itself and said diameter, and means carried by the head positively engaging the abutments alternately upon opposite sides of the axis. 90 95
15. A ratchet mechanism comprising a support, a wheel journaled upon the support and provided with a plurality of concentrically arranged circles of abutments, a head extending diametrically of the wheel, means to reciprocate the head laterally relative to itself and said diameter, and means carried by the head at electively variable positions between the middle and its ends and positively engaging the elected circles of abutments alternately upon opposite sides of the axis. 100 105
16. A ratchet mechanism comprising a support, a wheel journaled upon the support and provided with a plurality of concentrically arranged circles of shoulders, a head extending diametrically of the wheel, manual means at one side of the wheel to reciprocate the head laterally relative to itself and said diameter, and means carried by the head at electively variable positions between the middle and its ends and positively engaging the elected circles of shoulders alternately upon opposite sides of the axis. 110 115
- In testimony whereof we have signed our names to this specification. 120 125
